UNITED STATES PATENT OFFICE.

ROBERT B. KERNOHAN, OF PITTSBURG, PENNSYLVANIA.

GAS-PRODUCER.

940,696.

Specification of Letters Patent. Patented Nov. 23, 1909.

Application filed April 13, 1909. Serial No. 489,628.

To all whom it may concern:

Be it known that I, ROBERT B. KERNOHAN, residing at Pittsburg, in the county of Allegheny and State of Pennsylvania, a citizen 5 of the United States, have invented or discovered certain new and useful Improvements in Gas-Producer, of which improvements the following is a specification.

The invention described herein relates to 10 certain improvements in gas producers and has for its object a construction wherein provision is made for the relative movements of the producer body and a poker extending into the same and a movement of the poker 15 toward and from the axis of the producer, whereby a thorough stirring up or agitation of the fuel can be effected.

The invention is hereinafter more fully described and claimed.

20 In the accompanying drawings forming a part of this specification, Figure 1 is a sectional elevation of my improved producer; Fig. 2 is a similar view, illustrating certain modifications in the construction of 25 the producer and Fig. 3 is a sectional detail view on an enlarged scale of the construction of poker shown in Fig. 1.

In the construction shown in Fig. 1 the producer body 1 is supported preferably by 30 means of beams 2 to which the shell of the producer is secured adjacent to its upper end. The producer is covered by a metal plate 3 having an opening therethrough for the passage of fuel into the producer said 35 opening being normally closed by a bell 4. This bell is supported by a weighted lever 5 in its closed position so as to prevent the discharge of coal from the receptacle 6 into which the coal is deposited by an oscillating 40 cup 7 which is normally in position with its open end in line with the lower end of a chute 8 in which the coal is placed. The oscillation of this cup or receptacle from 45 position in line with the mouth of the chute, is effected by any suitable means, such as an eccentric 9 on a driven shaft 10. By the operation of this eccentric the receptacle would be shifted to a position to deposit the coal received from the chute, into the 50 receptacle 6. While moving to this position the lower end of the chute is closed by the curved underside of the cup or receptacle. As soon as in its return movement, the receptacle comes into line with the opening 55 from the chute 8, a projection 11 on the underside of the receptacle will depress the

bell 4 and permit the discharge of coal into the producer.

By properly timing the rotation of the shaft 10 the supply of coal delivered to the 60 producer can be maintained at a rate uniform with the combustion of the coal in the producer. The lower end of the body of the producer extends down into a basin 12 adapted to contain water to seal the lower 65 end of the producer. This basin, in the construction shown in Fig. 1, is rotatably supported by any suitable means, preferably by rollers 13.

A poker 14 is carried by the basin 12 in 70 such position that its upper end will extend up a suitable distance into the body of the producer 1. It is preferred that the poker should extend up a distance sufficient to prevent an agglomeration of the highly heated 75 ashes or unconsumed elements of the fuel; or to break such agglomeration which may occur. The melting or softening of the material, which when melted will form the clinker, undoubtedly occurs at the hottest part of a 80 producer, and the solidification to clinker forms below that point, and where the heated materials will be subjected to the cooling effects of the blast. In the construction shown in Fig. 1 the poker is supported by 85 the basin in a position eccentric to the axis of the producer and to the axis of rotation of the basin. While being carried around by the basin, the poker is shifted so that the portion within the producer will move in a 90 direction at an angle to the direction in which it is carried by the basin. While not limiting the invention in regard to the character of movement of the portion of the poker within the producer, it is preferred 95 that each portion should move in the arc of a circle having its center eccentric to the orbit of the poker around the axis of the producer. In the construction shown in Fig. 1 the lower end of the poker extends 100 down through a boss formed on the basin 12 and to its lower end is secured a pinion 16 adapted to intermesh with a circular rack 17 formed in the inner periphery of the annular plate 18 supporting the basin. As the basin 105 is rotated, which may be effected by any suitable means, such for example as that shown, consisting of a power driven pinion 19 intermeshing with the rack 20 on the basin, the poker will be carried around in 110 the producer and will also be given a motion around the axis of the portion mounted in

the basin. If the inner end of the poker be curved or bent as shown, this rotation on its axis will cause the inner end to move in the arc of a circle eccentric to the axis of the 5 producer, while moving around the axis of the producer. The blast pipe 21 for introducing air and steam or both into the producer, is supported by the basin and is provided with a distributing head 22, located 10 within the body of the producer.

The poker is made hollow as shown and a pipe 34 for introducing a cooling fluid extends nearly to the upper end of the poker. In the construction shown in Fig. 1, where 15 the poker is carried around the axis of the producer by the rotating basin, the lower end of the pipe 34 is connected to a disk 35 carried by the blast pipe 21 which is located at the center of the arc of rotation of the 20 basin and poker. A groove 36 is formed in one face of this disk and is connected to the pipe leading to the poker. A second disk 37 is loosely mounted on the blast pipe and is provided with a groove corresponding to 25 that in the disk 35, said groove being connected to the supply pipe 38. These disks are held tightly in contact, and the annular passage formed by the grooves therein forms a connection between the supply pipe and 30 the pipe 34.

In the construction shown in Fig. 2, provision is made for the rotation of the producer body itself, while the basin and the top plate 3 remain stationary. As shown 35 the top plate is made independent of the producer body, but a water-sealed joint 23 is formed between the top and the body. The body of the producer is supported upon posts 24, preferably through the medium of rollers 40 or 25 on which rests a flange 26 secured to the producer body. While the body may be rotated by any suitable means, it is preferred to form teeth in the outer periphery of the flange 26, with which teeth a driven 45 pinion 27 will engage. As before stated the basin 12 in this construction is stationary and a bevel pinion 28 is secured to the lower end of the poker, said pinion intermeshing with a corresponding pinion on the shaft 50 29, which may be driven from the same shaft of the pinion 27 or independent thereof. In this construction the body of the producer is carried around the poker while the portion of the latter within the producer is 55 caused to move in direction at an angle to the movement of the producer.

In lieu of the construction shown in Fig. 1 for effecting the automatic feed of the coal to the producer, a rotatable receptacle 7^a 60 is mounted in the chamber 6, said receptacle being rotated by the shaft 30. The movement of the bell to permit the coal to drop into the producer is effected by means of an eccentric 31 on the shaft 30, having its 65 strap 32 connected to the lever 5.

It is preferred to form screw threads on the lower portion of the poker which will tend to force the ashes up away from the bearing of the lower end of the poker in the basin and the lower portion of the threaded part is formed with a lateral extension 33, which will tend to sweep the ashes out away from the poker and toward the vertical wall of the basin, thus facilitating the removal of the ashes from the latter and preventing them banking up around the blast device. 70

In order to protect the bearing of the poker from ashes, a cone-shaped shield 39 may be secured to the basin and extend up around the poker to a point above the level 80 of the water in the basin, and an annular apron 40 is secured to the poker above the shield and extends down around the shield. While it is believed that the shield and apron will exclude all ashes from around 85 the bearing of the poker one or more openings 41 may be formed through the bottom of the basin within the shield.

As the upper portion of the poker, especially that part within the hottest zone is 90 more rapidly destroyed provision is made for the renewal of the upper portion, which is separable from the lower portion. A suitable construction for this purpose is shown in Fig. 3, and consists in enlarging the upper end of the lower portion of the poker for the reception of a nipple 42 on the removable section. This nipple fits loosely in the socket in the lower portion, and has a curved seat therein so as to maintain a tight 100 joint and prevent the escape of any material amount of cooling fluid. The removable section is provided with a flange 43 above the nipple, said flange having an angular recess in its underside for the reception of 105 a similarly shaped boss or projection 44 on the lower portion of the poker.

When it is desired to renew the poker, the fuel is allowed to burn down sufficiently far to permit of the fuel being shoved aside to 110 uncover the point of junction between the two sections. The worn-out section is then drawn up through an opening 45 in the top plate and a new section placed in position. It is preferred to form a thread 46 on the 115 removable section, of such a pitch as to force the fuel or ashes upward away from the joint between the sections. The downward thrust due to the action of the thread on the ashes will tend to hold the two sections of 120 the poker tightly together.

Where the cooling fluid is discharged through a port 48 from the lower end of a vertically arranged poker, air bubbles are apt to form in the upper ends of the poker, 125 preventing the cooling fluid from contact therewith. In order to overcome this difficulty a second tube 47 is arranged in the poker and extends to a point closely adjacent to the upper end of the chamber in the 130

poker. This pipe will serve not only for the escape of air but also as an auxiliary outlet for the cooling fluid.

I claim herein as my invention:

- 5 1. A gas producer having in combination a body portion, a poker projecting upwardly into the body portion, means for moving one of said parts around the axis of the producer, and means for introducing air within
  - 10 the producer, the poker extending above the point of entrance of the air.
  - 2. A gas producer having in combination a body portion, a poker projecting upwardly into the body of the producer, means for
  - 15 moving one of said parts around the axis of the producer, and means for shifting the portion of the poker within the producer in a direction at an angle to the circle described by the moving part.
  - 20 3. A gas producer having in combination a body portion, a poker projecting upwardly into the body of the producer, means for moving one of said parts around the axis of the producer, and means for causing a portion of the poker within the producer to move in the arc of a circle eccentric to the axis of the producer.
  - 25 4. A gas producer having in combination a body portion, a bent poker projecting upwardly into the body of the producer, means
- for moving one of the parts around the axis of the producer and means for rotating the poker on the axis of the lower portion.
- 5. A gas producer having in combination a movable body portion, means for rotating 35 said body portion, a bent poker projecting upwardly into the body portion and means for rotating the poker.
  - 6. A gas producer having in combination therewith a poker provided with a detachable section removable without disturbing the other portion of the poker when the latter is in position within the producer.
  - 7. A gas producer having in combination a hollow poker having an upward inclination 45 into the body of the producer and provided with a main outlet for the cooling fluid located at a point distant from the inner end of the poker, means for introducing a cooling fluid into the poker, and an auxiliary 50 discharge pipe having its inlet opening located at a point adjacent to the inner end of the cavity in the poker.

In testimony whereof, I have hereunto set my hand.

ROBERT B. KERNOHAN.
